MAGAZINE FIREARM.

(Application filed Mar. 7, 1902.)

(No Model.)

UNITED STATES PATENT OFFICE.

CHARLES A. YOUNG, OF ENON, OHIO.

MAGAZINE-FIREARM.

SPECIFICATION forming part of Letters Patent No. 709,385, dated September 16, 1902.

Application filed March 7, 1902. Serial No. 97,190. (No model.)

To all whom it may concern:

Be it known that I, CHARLES A. YOUNG, a citizen of the United States, residing at Enon, in the county of Clark and State of Ohio, have 5 invented certain new and useful Improvements in Magazine-Firearms; and I do hereby declare the following to be a full, clear, and exact description of the invention, such as will enable others skilled in the art to which it app- 10 pertains to make and use the same.

My invention relates to firearms of the repeating kind; and it consists of improvements in various parts of such a firearm as is shown and described in Letters Patent of 15 the United States granted to me and Silas H. Barton, dated June 18, 1901, and numbered 676,809. In describing my present improvements I shall follow substantially the language employed in the aforesaid patent so 20 far as the same is appropriate and add to the same a description of my present improvements and modifications, and the claims here- 25 to appended will also indicate and define the several features of novelty.

In the accompanying drawings, illustrating 30 the improvements, Figure 1 is a longitudinal sectional view showing the barrel opened, taken on line $x-x$, Fig. 2, some parts being in full lines. Fig. 2 is a transverse sectional view taken on the plane $y-y$ looking to the right. Fig. 3 is a transverse sectional view taken through the barrel, the magazine, and the sliding grip or fore-arm. Fig. 4 illustrates the details of the extractors on the breech-block. Fig. 5 is a detail view of the shell-carrier bottom. Fig. 6 is a side view, 35 partially in section, showing the position of the mechanism when the barrel is closed against the breech-block. Fig. 7 is a view of the under side of Fig. 6, parts being in section. Fig. 8 is a view, partially in section, 40 illustrating the connection between the sliding fore-arm or grip and the barrel. Fig. 9 is a plan view of the under side of the rear 45 portion of the barrel. Fig. 10 is an oblique projection depicting the barrel-latch, the magazine-stop, and cartridge-carrier and ap- purtenant construction. Fig. 11 is a sec- 50 tional detail on the line $z-z$, Fig. 10.

Like parts are represented by correspond- 55 ing characters of reference in the several views.

As in the gun described in the Letters Patent hereinbefore referred to, I preferably employ a single barrel a , slidably mounted upon 55 a breech-block frame, that also carries or sustains the other operative parts of the gun. Beneath the barrel is a magazine b . The barrel is constructed to fit when closed against the breech-block c , and in the frame immedi- 60ately in the rear of the magazine b is an open chamber d , normally closed at the top by the breech end of the barrel a and normally containing the spring-actuated cartridge or shell 65 carrier e .

The magazine b consists, preferably, of a straight cylinder of sufficient length to contain the desired number of cartridges and provided with a spring (not shown) adapted to feed the cartridges rearwardly, substan- 70 tially as in the former patent referred to. The rear of the magazine is provided with a spring-held catch b^2 , consisting of an orificed plate, the orifice being of the same size as the bore of the magazine. This catch b^2 is held 75 normally upward by springs b^3 , so that the lower part of the catch stands above the bottom of the magazine and forms a stop for the rearmost shell or cartridge and precludes its 80 release until the barrel is nearly closed against the breech.

As in the patent hereinbefore referred to, the barrel a is slidably connected to the breech-block frame. For this purpose that portion of the frame above the magazine is 85 made with inwardly-projecting ribs b^4 , engaging longitudinal grooves or ways a^4 on the bottom of the barrel, and the barrel can be moved back and forth on the frame by means of a sliding handle or grip f . This handle 90 or grip surrounds the magazine and in the present instance is secured to the barrel by means of a pin e^6 , passed transversely through the grip and a slot f^2 in a solid tongue f' on the under side of the barrel. The upper side 95 of the sliding handle or grip has securely seated in it a metallic block f^3 , made with a slot or groove f^4 , into which the tongue f' of the barrel projects, and the slot or recess f^4 is of such length that the thrust of grip in 100 moving the barrel back and forth is borne by the block f^3 in the grip and not by the connecting-pin e^6 . The function of the pin e^6 is to hold the barrel and grip together when and

after these parts are removed from the breech-block frame. The metallic block f^3 in the grip is extended rearwardly and is made at its rear end with a laterally-projecting cam-face f^5 . The groove a^5 in the bottom of the barrel preferably extends from the point where the grip is attached rearwardly to the end of the barrel, and the barrel is further provided on the bottom with two cross-grooves a^8 and a^9 , the rear edges of which are formed square, so as to constitute holding-shoulders; but in the present instance the rear edge of the forward cross-groove a^9 is formed of a wedge-shaped dovetailed piece a^{99} , fitting in a transverse dovetailed seat in the bottom of the barrel and held in place by a set-screw passed through a slot in the wedge-shaped piece and entering a threaded hole in the barrel. The adjustability of the wedge-shaped shoulder permits compensation for wear, and therefore a close fit of the breech of the barrel against the breech-block, as will presently appear. The cross-grooves a^8 and a^9 are adapted to operate in connection with a lock or latch to hold the barrel in its closed position and to limit its movement in opening and closing. The lock or device for holding the barrel consists of a perforated plate a^{10} , that extends downwardly around the magazine and is adapted to be pressed upwardly by the springs a^{11} . The opening through this plate is elongated, so that it may move up or down on the magazine. The upper edge a^{12} of the plate a^{10} is adapted to fit into either of the cross-grooves a^8 and a^9 and engage the shoulders on the barrel. Resting on an inclined shoulder in the forward side of this lock-plate is one arm a^{13} of a rock-shaft or lever a^{14} . This rock-shaft or lever extends forwardly through the fore-arm or frame-piece and is shown to be provided at its opposite end with an arm or finger a^{15} , positioned to contact with the laterally-projecting cam-face f^5 on the grip or handle. The grip and its projecting cam are so positioned with reference to the barrel that the cam passes over the arm a^{15} just before the barrel is closed. When the barrel is closed, the arm a^{15} stands forward of the cam-face f^5 , with the handle or grip moved to the rear. The springs a^{11} thus move the latch-plate a^{10} until the edge a^{12} thereof engages the cross-groove a^9 , and thus firmly locks the barrel against the breech-block. The first outward movement of the handle f , (independent of the barrel,) which is permitted by the slotted opening f^2 working on the pin e^6 , will cause the cam-face f^5 to move over the arm a^{15} , and thus depress the same and through the medium of the rock-shaft or lever a^{14} depress the latch-plate, and thus liberate the barrel. A further movement of the handle will then carry the barrel outward until the latch-plate automatically engages the cross-groove a^8 and stops the same. The magazine-stop b^2 is provided with a small upwardly-extending projection b^5 , over which the groove a^5 in the bottom of the barrel travels, and pivoted in

a lateral recess in said groove is a spring-pressed cam-latch a^{16} , standing normally across the groove and held against movement in one direction by suitable shoulders, but free to move in the opposite direction so as to stand flush with the side of the groove. This cam-latch a^{16} is adapted when the barrel is being closed to strike the projection b^5 on the magazine-latch and force the same downward until the opening therein will coincide with the bore of the magazine, and thus permit the ejection of a shell or cartridge into the carrier e , immediately in the rear and under the breech of the barrel. As soon as the cam a^{16} in the closing of the barrel has passed the projection b^5 the catch will be promptly pressed upward to catch and retain the next succeeding shell or cartridge. As the barrel is opened the cam-latch a^{16} will be turned out of the way, so as not to operate the magazine-stop until the barrel is again closed, the spring-latch having as soon as it has passed the projection b^5 returned to its normal position across the groove a^5 and in position to strike and operate said projection and magazine-latch when the barrel is closed again.

As in the former patent herein referred to, the cartridge or shell carrier e consists of a U-shaped frame mounted on the end of a spring-pressed lever e' , the lever being preferably provided with an extended finger e^2 , that fits in the round opening e^3 in the bottom of the carrier, so that the carrier is pivoted on the arm. The finger e^2 is also preferably pivoted on the end of the arm e' , as shown at e^4 , and thus a universal connection is established between the spring-actuated lever e' and the U-shaped frame of the carrier. The arm e' extends rearward through an opening below the breech-block and is pivoted at e^5 under the firing mechanism, a spring e^9 , placed between the frame and the lever, normally tending to throw the forward end of the arm and the carrier upward. The forward edges of the carrier are beveled and adapted to be engaged by the breech end of the barrel when being closed to force the carrier downward into the chamber d behind the magazine. The inner side of the carrier can be provided with a small spring-actuated finger e^7 , the upper end of which is normally pressed inward, so as to lightly hold the shell therein. When the carrier is depressed, a small inward projection e^8 in the wall of the chamber d will force the upper end of the finger e^7 outward, so that it will lie flush with the side of the carrier and not prevent ingress of a shell from the magazine. The sides of the chamber d are also preferably recessed, as shown at d' , to receive the sides of the carrier. In the present instance the carrier is further provided in one of its walls (made shorter than the other) with an inwardly-extending finger e^{10} , held to normally project over the cavity of the carrier by means of a spring e^{11} , pressing against a corresponding

finger e^{12} on the lower end of the shank of both fingers. The lower finger e^{12} is operated by the inner end of a pin e^{13} , the forward end of which protrudes beyond the forward end of the carrier and is pushed inward by the barrel when the latter is closed to release the carrier from the shell. The carrier-finger e^{10} not only holds down the cartridge or shell when the barrel is closed thereon to load, but also serves as a device to strike the discharged shell and eject the same when the carrier is thrown up to load. In the present instance the carrier is also provided with a supplementary bottom piece e^{14} , hinged at e^{15} in the forward end of the carrier and pressed normally upward by a spring e^{16} . The rear end of the supplementary bottom e^{14} engages the rim of the cartridge to prevent it from moving forward when the gun is discharged. In the rear end of the bottom of the carrier is a notched stop and rest e^{17} , that limits the entrance of the shell to the carrier and affords a seat for the lower side of the rim of the shell.

At each side of the breech-block, fitted in suitable recesses therefor, are small spring-actuated blocks, constituting extractors c^2 , pivoted at points therein forward of their rim-engaging ends, such engaging ends being of beveled hook shape and adapted to engage and hold the rim of the cartridge or shell, and the barrel is notched out at each side to receive the spring-actuated extractors, and the construction is such that a shell or cartridge being in the carrier and the barrel closed the carrier will as the barrel is opened force the shell or cartridge upward, with the rim of the shell resting firmly against the breech-block and engaged by the extractors, the shell being held by the finger e^7 and the supplementary bottom piece e^{14} , so as to properly enter the barrel as the latter is closed, after which the pressure of the end of the barrel on the carrier depresses it back to its position in the rear of the end of the magazine, the action of the barrel on the pin e^{18} turning the finger e^{10} out of the way. In the breech-block below the firing-pin is a spring-actuated pin h^{20} , having its head made with an angular seat, that engages the lower edge of the rim of the shell to prevent any tendency of the carrier to drag the shell down as it is depressed. This pin protrudes from the breech-block when the barrel is drawn from the breech-block, but is pushed back when the barrel is closed against the breech. The projected head of the pin h^{20} does not obstruct the upward movement of the cartridge and carrier, because the cartridge in its upward movement is held down at its forward end by the end of the outmoving barrel and tilted, and the rear end of the cartridge will pass upward and around the pin in a curved path.

As in the former patent hereinbefore referred to, h designates the spring-actuated firing-pin, the reduced end of which extends forward through the breech-block in the usual

way and is when released forced against the cartridge by a spring h' . When cocked, the firing-pin is held in position by a sear h^2 , the rear end of which engages a notch h^3 in the rear end of the firing-pin. At one side of the firing-pin there is pivoted a cocking-lever h^4 , that is adapted to engage a laterally-projecting finger h^5 on the firing-pin. This cocking-lever is pivotally connected to a reciprocating cocking-rod h^6 , that extends forward along one side of the open chamber d to the forward end of the frame, where it has a hook-shaped end that is engaged by a corresponding hook-shaped end of a similar rod h^{66} , slidably attached to the grip or handle f . The connection between the rods h^6 and h^{66} is sliding, so that the grip or handle can have a limited movement without moving the cocking-rod h^6 , the construction being such that as the barrel is moved forward just before it reaches the limit of its stroke the cocking-lever h^4 is pulled back by the rod h^6 and, impinging the firing-pin, cocks the gun; but when the grip and magazine are to be removed from the breech-block frame the hook-shaped ends of these rods h^6 and h^{66} spring apart and separate. In the frame immediately below and parallel to the firing-pin is a spring-actuated safety-pin h^{21} , the rear end of which is projected by its spring to lie above an arm h^{22} on the sear h^2 to prevent the sear from being operated by the trigger until the gun is closed. On the forward end of the safety-pin h^{21} is a lateral projection h^{23} , that is operated by the forward edge of the cocking-arm when the gun is closed to withdraw the rear end of the safety-pin h^{21} from its position above the arm h^{22} on the sear, so that the sear can only be operated and the firing-pin released when the barrel has been firmly closed against the breech-block. To prevent accidental release of the firing-pin at other times, I can provide an additional safety-catch consisting of a sliding block h^{24} , having a rearwardly and downwardly extending hook-finger h^{28} to engage a notch h^{44} in a rear extension h^{55} of the sear. The sliding block h^{24} can have a spring-catch h^{26} to engage notches h^{27} in the frame for the two positions of the safety-catch. The cocking-rod h^6 is shown to have a lateral projection h^{77} to enter and engage a groove e^{18} in the side of the carrier to hold the carrier down and prevent it from rising until the proper moment.

The latch a^{10} is furnished at its lower end with a hook projection a^{20} , that is engaged by finger-piece d^3 , pivoted at d^4 in the frame. This finger-piece also engages a projection d^5 on the under side of the magazine, so that by pressing down the single finger-piece both the barrel and magazine can be separated from the breech-block frame. When the barrel and grip and magazine are thus separated from the breech-block frame, the barrel and grip and magazine are still held together by the pin e^6 , provided, of course, the said pin has not been previously removed.

The operation of the gun, which can also be gathered from the description of its several parts, is as follows: The gun is opened and the magazine filled with a number of 5 shells or cartridges. If desired, a shell can be placed in the carrier and one in the barrel, the carrier, with the shell or cartridge therein, being pressed down, so as to permit the barrel to be closed. After the gun has been fired the 10 outward movement of the grip or handle will unlock the barrel, and a further movement of the handle will carry the barrel and cocking-arm forward. The shell or cartridge being engaged by the extractors c^2 will be extracted 15 from the barrel and held on the breech-block. As soon as the barrel and cocking-arm are sufficiently far forward the spring-actuated arm e' will throw the carrier e upward, and the finger e^{10} , while retaining the charged 20 shell, will strike the empty shell or cartridge and force the latter vertically off the breech-block. When the barrel is again closed, a fresh shell or cartridge runs into the barrel, with the rim engaged by the extractors c^2 , and 25 the carrier will be again pressed down into its place in the rear of the magazine and in position to receive another charged shell or cartridge.

In the drawings I have illustrated my improvements as applied to a shotgun; but obviously the improvements are equally applicable to a rifle.

What I claim, and desire to secure by Letters Patent, is—

1. In a firearm, the combination of a breech-block frame, a sliding barrel thereon and a sliding grip, a slotted tongue on the under side of the barrel and a metallic piece seated in the sliding grip having an elongated recess 30 to receive the slotted tongue, and a pin engaging the metallic piece and passing through the slot of the tongue to connect the grip and barrel, said slot being of such length that the thrust of the grip on the barrel shall be borne 35 by the contact of the ends of the tongue and recess in the metallic piece and not by the connecting-pin.

2. The combination of the breech-block frame, a sliding barrel thereon, a magazine 40 under the barrel, a chamber in the breech-block frame under the breech of the barrel in the rear of the magazine to receive the carrier, the carrier, a spring-actuated finger in said carrier to project inward over the upper 45 end of the carrier when the barrel is opened and means actuated by the end of the barrel to turn said finger out of said position when the barrel is closed, substantially as described.

3. The combination of a breech-block frame, 50 a sliding barrel thereon, a chamber in the breech-block frame under the breech of the barrel to receive a cartridge or shell carrier, the carrier, a movable finger in said carrier, means to hold said finger to project inward 55 over the upper end of said carrier when the barrel is opened and means actuated by the

barrel to turn said finger out of said position when the barrel is closed.

4. The combination of the breech-block frame, a sliding barrel thereon, a magazine 70 under the barrel, a chamber in the breech-block frame under the breech of the barrel and in rear of the magazine to receive the carrier, the carrier and a spring-actuated movable bottom in the carrier. 75

5. The combination of the breech-block frame, a sliding barrel thereon, a magazine under the barrel, a chamber in the breech-block frame under the barrel, and in rear of the magazine to receive the carrier, the 80 carrier, and a spring-actuated movable bottom in said carrier hinged at its forward end to the forward end of the carrier and adapted to engage the rim of the shell to hold said shell in the carrier. 85

6. The combination of the breech-block frame, a sliding barrel thereon, a magazine under the barrel, a chamber in the breech-block frame under the breech of the barrel and in rear of the magazine, the carrier, a 90 cocking-rod actuated when the barrel is opened and closed, a projection on said cocking-rod adapted to engage said carrier to hold the same when in the chamber and to release the same when the barrel has been 95 opened a predetermined distance, substantially as described.

7. In a firearm the combination of a breech-block frame having a breech-block, a barrel sliding on the breech-block frame toward and 100 from the breech-block, and shell-extractors in the sides of the breech-block and in line with the barrel consisting of small blocks having rim-engaging rear ends and pivoted at their forward ends and springs for holding the rim-engaging ends inward toward each other, substantially as described. 105

8. The combination of the breech-block frame, a sliding barrel thereon, a spring-actuated latch to limit the forward movement 110 of the same, a magazine under the barrel having a catch, and a finger-piece on the breech-block frame engaging both the barrel-latch and magazine-catch and adapted to be operated to simultaneously release the barrel 115 and magazine from the breech-block frame.

9. In a firearm the combination of the breech-block frame and breech-block, a barrel sliding on the breech-block frame, a shell or cartridge carrier, spring-actuated extractors in the sides of the breech-block, to catch and hold the sides of the rim of the shell when the latter is pushed rearwardly on the carrier by the barrel, and a spring-protruded seat in the breech-block constructed to support the shell at the lower edge of its rim, 120 substantially as described. 125

10. In combination with a breech-block frame, a sliding barrel thereon, a spring-actuated firing-pin, a sear to engage and hold 130 the same when cocked, a cocking-lever adapted to cock said firing-pin when the barrel is

moved forward, a spring-actuated safety-catch to prevent the operation of the sear when the barrel is moved forward and arranged to be operated by the cocking-lever upon the closing of the barrel to release the sear.

11. In combination with the breech-block frame, a sliding barrel thereon, a spring-actuated firing-pin, a sear to engage and hold the same when cocked, a cocking-lever adapted to cock said firing-pin when the barrel is moved forward, a spring-actuated safety-catch to prevent the operation of the sear when the barrel is moved forward and arranged to be operated by the cocking-lever to release the sear when the barrel is being closed, and a manually-operated safety-catch

to engage and lock the sear when the barrel is closed.

12. The combination of a breech-block frame, a sliding barrel thereon, a chamber in the breech-block frame under the breech of the barrel to receive a cartridge or shell carrier, the carrier, a finger turning on a vertical pivot in the side of the carrier to be turned laterally across the top of the same and means for yieldingly holding said finger across the top of the carrier.

In testimony whereof I affix my signature in presence of two witnesses.

CHARLES A. YOUNG.
